UNITED STATES PATENT OFFICE.

JAMES HENRY KIRK, OF STALYBRIDGE, ENGLAND.

ENAMELED METAL TABLET OR PLATE FOR FACING WALLS, CEILINGS, OR THE LIKE.

SPECIFICATION forming part of Letters Patent No. 792,661, dated June 20, 1905.

Application filed May 9, 1904. Serial No. 207,122.

To all whom it may concern:

Be it known that I, JAMES HENRY KIRK, a subject of the King of Great Britain, residing at The Ashes, Stalybridge, Cheshire, England, have invented new and useful Improvements 5 in Enameled Metal Tablets or Plates for Facing Walls, Ceilings, or the Like, of which the following is a specification.

My invention relates to the manufacture of 10 enameled metal tablets or plates designed to be applied to walls, ceilings, and other surfaces and to present the appearance of enameled bricks or of tiles and the like, the object of my invention being to produce tablets of 15 this class which shall be cheaper and at the same time possess greater strength and be more secure when fixed than tablets of the same class as heretofore manufactured.

In carrying out my invention I provide 20 metal blanks of square, oblong, rhombic, rhomboidal, or other suitable shape, according to the pattern to be produced by the tablets, and I bend two or more of the edges of 25 each tablet so as to form semicircular flanges which when the tiles are placed upon a bed of mortar, cement, or other fixing material form keys to prevent the tablets from becoming detached.

To enable my invention to be fully understood, I will describe the same by reference 30 to the accompanying drawings, in which—

Figure 1 is a blank suitable for forming a tablet of a shape corresponding with the end of a brick. Fig. 2 is a rear view of the tablet having the bent edges, and Figs. 3 and 4 are sections on 35 the lines 3 3 and 4 4, respectively, of Fig. 2. Fig. 5 is an elevation drawn to a smaller scale than Figs. 1 to 4, showing a series of tablets of a size intended to represent bricks fixed 40 upon a wall; and Fig. 6 is a section on the line 6 6, Fig. 5, illustrating the method of fixing. Fig. 7 is a view similar to Fig. 3, illustrating a modification. Fig. 8 is a rear view of a diamond-shaped or rhombic tablet.

45 *a* indicates the blank from which the tablet is formed, and *b b* the edges of the same which are bent over to a semicircular form and constitute keys, the corners of the said blank being cut away—for instance, as shown in Fig. 50 1—in such a manner that when the edges are

bent over, as described, the ends of these bent-over edges will lie against one another, as indicated at *c* in Fig. 2. The bending of the edges may be effected by stamping in a machine or by any other suitable means. 55

The plate when bent is coated with white, black, tinted, or colorless or other suitable enamel, or a pattern in enamel may be stenciled upon it, or enamels of varying color may be applied in order to give it the effect of 60 marble, or it may be otherwise decorated in enamel in any suitable manner. The backs of the tiles and those parts which are not exposed to view may also be enameled, or they may be varnished or coated with a paint or 65 other material which will protect them from corrosion. The plates are then fixed by laying them upon a bed of plastic cement, as indicated in Fig. 6, so that the cement enters the keys on the edges of the plate. As shown 70 in Figs. 5 and 6, a series of tablets of the shape of ordinary bricks are laid together to represent enameled bricks.

It will be noticed that between adjacent tiles channels, as at *d*, Fig. 6, are formed. 75

Instead of applying the tablets direct upon the surface to be ornamented they may be applied to tiles, the tiles with the tablets upon them being then fixed in the usual manner of 80 fixing tiles.

In the foregoing description I have referred to tablets having all the edges bent over. This, however, is not essential, as, for instance, the bending over of opposite edges would afford sufficient key, but in this case 85 the edges which are not bent over to form keys are curved slightly inwardly, as shown in Fig. 7, so that when adjacent tiles come together there will be no variation of the channels *d* between adjacent tiles. 90

As hereinbefore stated, tablets of any suitable form may be employed. In Fig. 8 I show a tablet of rhombic form, a series of which can be laid together, as hereinbefore described. 95

By adopting the semicircular form of edge, as hereinbefore described, I am enabled to form tablets from a thinner gage of metal than would otherwise be possible, as the effect of the bending of the edges, as hereinbe- 100

fore described, is to impart great rigidity to the tablets.

It is to be understood that the tablets may be composed of iron, steel, copper, or any other metal suitable for the purpose.

I can, if desired, roughen the backs of the tablets by applying thereto, by means of cement or otherwise, pieces of broken glass, sand, grit, or other substance which will 10 serve as an additional key for retaining the tablets in position.

Having now particularly described and as-

certained the nature of my said invention and in what manner the same is to be performed, I declare that what I claim is—

A metal tile having edge portions bent rearwardly and curving outwardly, said outwardly-curved portions being semicircular in cross-section, substantially as described.

JAMES HENRY KIRK.
